UNITED STATES PATENT OFFICE.

LOUIS S. DAY AND BENNETT S. LEWIS, OF NEW HAVEN, CONNECTICUT.

FEED ATTACHMENT TO METALLIC-CARTRIDGE-CRIMPING MACHINES.

SPECIFICATION forming part of Letters Patent No. 228,447, dated June 8, 1880.

Application filed March 8, 1880. (Model.)

To all whom it may concern:

Be it known that we, LOUIS S. DAY and BENNETT S. LEWIS, of New Haven, in the county of New Haven and State of Connecticut, cut, have invented a new and Improved Feed Attachment to Machines for Crimping Metallic Cartridges, of which the following is a specification.

The object of our invention is both to feed the cartridges to the crimping-machine and to feed them with the front end foremost.

The invention consists in new elements and in novel combinations, as the same are herein-after more fully set forth and claimed.

In the drawings, which are hereby made a part of the specification, Figure 1 is a perspective view of the attachment, a portion of the case and of the hollow frustum being removed to show the parts of the attachment, and a portion of the hopper being also removed. Fig. 2 is a top view of a circular plate having a cam on its upper side. Fig. 3 is a view of the under side of a circular plate having slides and circular slots. Fig. 4 is a view of the central jointed shaft having an arm and roller. Fig. 5 is a view of a metallic cartridge. Fig. 6 is a vertical and central section of the attachment.

To enable others to make and use our attachment, we will describe it in detail.

A is a cylindrical case inclosing all the parts of the attachment except the hopper and agitator. It has a downwardly-inclined rim, *a*, attached on the inside. A support attached to the case holds the breech *b*. Two like supports (one not being shown) support the hopper. The hopper *B* is made in the form shown in the drawings, and is provided with the slide *e*, which varies the size of the opening into the agitator. The agitator *C* has one end loosely attached to the hopper, and the other end rests on the central shaft, *D*. The central stationary shaft, *D*, rests on the cross-piece *f*, passes through the circular plates, and is made in two parts, which are united by a joint, the upper part having an arm, *g*, on the end of which is a heavy roller, *h*. To the upper end of the shaft one end of the spiral spring *i* (represented by dotted lines) is attached, which, passing under the agitator, has its other end attached to the case. The broken lines on

agitator *C* represent a piece crossing the agitator on its under side. Into a hole in this piece the upper end of the stationary shaft is inserted.

The circular plate *E*, Fig. 3, has three circular slots, one end of each slot being enlarged, as shown in Fig. 3, and has also the slides *l*. In the slides *l* the pins *x*, Fig. 3, are inserted, and run in the cam *m*, Fig. 2. These slides partially close the enlarged ends of the slots during the revolution of the plate, and hold the cartridges by their heads until they are over the hole *n*, Fig. 2, when they are drawn back by the pins *x* in the cam and let the cartridges drop. The plate *E* has a sleeve, as shown in Fig. 6, which extends downward around the stationary shaft, to which the pulley is attached, to impart motion. The hollow frustum *F*, Figs. 1 and 6, is attached to the plate *E*. The corrugations *o*, Figs. 1 and 6, are made on the plate *E*, or on a separate plate attached to it, and impart a vibratory motion to the arm on the central shaft.

The circular plate *H*, Fig. 2, has the piece *p*, 75 against which the ends of the cartridges hit, and the opening *n*, into which the pipe *s*, Fig. 6, is inserted and fastened to the said circular piece *H*. To this plate another plate is attached, having the cam *m*, made in the form shown in Fig. 2. The circular piece *H* is fastened to the case or frame and forms a part of the same.

The attachment being constructed as above described and as shown, the cartridges pass 85 through the hopper, down the agitator, between the hollow frustum and rim on the case, into the slots, and are suspended by their heads in the slots. As the plate revolves, the cartridges are brushed toward the enlarged ends 90 of the slots, and one cartridge passes into the enlargement and is held by the slide. When the enlargement is over the pipe in the lower plate the slide is drawn back by the cam and the cartridge drops into the pipe, which delivers it to the crimping-machine front end foremost, one cartridge from each slot dropping into the pipe at each revolution of the plate.

Having described our attachment, what we claim as new, and desire to secure by Letters Patent, is—

1. The hopper B, agitator C, jointed central shaft, D, provided with the arm g, having the roller h, spiral spring i, connected to the case and central shaft, corrugations o on the 5 revolving plate E, rim a, and hollow frustum F, in combination, to guide the cartridges into the curved slots, as shown and set forth.

2. The circular plate E, having a sleeve, as shown, and provided with the curved slots 10 having enlarged ends, also provided with the slides l, having the pins x, brush b, circular plate G, provided with the cam m and opening n, also fastened to the piece H, and pipe s, inserted in the opening n, in combination, to 15 deliver the cartridges to the crimping-machine, as shown and set forth.

3. The improved feed attachment herein described, consisting of the case A, having the rim a, hopper B, having the slide e, agitator 20 C, spiral spring i, central jointed shaft, D, pro-

vided with the arm g, having the roller h, hollow frustum F, circular plate E, having a sleeve, as shown, and corrugations o, and provided with the curved slots having enlarged ends, and with the slides l, having the pins x, 25 brush b, circular plate G, provided with the cam m, piece H, pipe s, cross-piece f, and driving-pulley, all the said parts constructed and in combination as shown and set forth.

4. In a feed attachment, the circular plate 30 E, having a sleeve, as shown, and provided with either one or more curved slots with enlarged ends, and with the slides l, having the pins x, and cam m, combined as shown and set forth.
